United States Patent Office

Des. 185,677
Patented July 14, 1959

185,677

SAFETY SPOON

George C. Matteson, Kansas City, Mo., assignor to Geo. C. Matteson Co., Kansas City, Mo., a partnership

Application December 29, 1958, Serial No. 53,948

Term of patent 7 years

(Cl. D44—29)

FIG. 1.

4—5. FIG. 2.

FIG. 3.

FIG. 4.

FIG. 5.

Fig. 1 is a top plan view of a safety spoon, showing my new design.

Fig. 2 is a side elevational view thereof.

Fig. 3 is a bottom plan view thereof.

Fig. 4 is a cross-sectional view taken on line 4—4 of Fig. 2; and

Fig. 5 is a cross-sectional view taken on line 5—5 of Fig. 2 of the safety spoon.

I claim:

The ornamental design for a safety spoon, as shown.
